Application February 11, 1946, Serial No. 646,910

14 Claims. (Cl. 114—150)

1

This invention relates to hydraulic steering mechanism for marine vessels, and for its general object aims to provide power steering controlled from the wheelhouse of the vessel, and which is especially characterized in that full rudder-torque hand steering is constantly available at the steering wheel in the event of power failure or a shutdown of the power unit.

It is a further and a particular object to provide a steering machine of this nature employing an electric motor as its energy source, and in which the said motor, and a responsive pump functional to the hydraulic fluid, are made to operate continuously.

With these and other objects and advantages in view, and which will appear and be understood in the course of the following description and claims, the invention consists in the novel construction and in the adaptation and combination of parts hereinafter described and claimed.

In the accompanying drawings:

Figure 1 is a top plan view portraying a steering machine produced in accordance with the now preferred embodiment of the present invention.

Fig. 2 is a side elevational view thereof with parts broken away and shown in longitudinal vertical section and, for simplicity in illustration, portraying only so much of the piping as is necessary to correlate the same to the various parts indicated.

Fig. 3 is a longitudinal vertical section taken on the substantial median line of the steering stand, and shown partly in elevation; and

Fig. 4 is a schematic plan view of the assembly.

The legends "R. R." and "L. R." appearing upon the drawings are intended to represent right rudder and left rudder, respectively, and these terms, as well as "front," "rear," "port" and "starboard," and other words of similar import, as hereinafter used, will be clearly understood and the parts and movements properly correlated where it is assumed that the rudder, denoted in the drawings by the numeral 5, lies to the rear and the other illustrated parts occupy positions to the front thereof. 6 designates the rudder post, and 7 a yoke attached thereto.

There are provided, and occupying positions one upon one side and the other upon the other side of a longitudinal median taken through the rudder post, two pairs of hydraulic engines, and in order to promote compactness of the machine the two engines of each pair are mounted one above the other. Each of these engines is comprised of a plunger and a closed cylinder

therefor, and I denote these plunger-cylinder assemblies by 8—9, 10—11, 12—13, and 14—15, respectively, the two first-named assemblies being the port engines and the two last-named assemblies being the starboard engines. From the plungers of the port engines respective rods 16 and 17 connect by a relatively stationary and common pivot-pin 18 with one arm 19 of the yoke, and one of the two starboard engines likewise finds its plunger connecting with the other arm 20 of the yoke by a relatively stationary pivot-pin 21, the rod for this latter plunger being designated 22. The remaining engine and which, as illustrated, is the upper of the two starboard engines, has its plunger 14 connecting through a rod 23 and by a pivot-pin 24 with the yoke-arm 20, but is distinguished from the previous said connections in that the pivot-pin and a supporting block 25 therefor are arranged for sliding movement relative to the yoke-arm in a direction tangential to a circle taken about the rudder post as an axis. Each pair of cylinders is swingably carried by a hinge pin, denoted 26 in the instance of the port set of cylinders and 27 in the instance of the starboard set of cylinders.

Connecting by its outer end with the block-carried pivot pin 24 and fulcrumed intermediate its length to the yoke-arm 20, as at 28, is a floating lever 30, and from the inner end of this lever connection is had by a pivot-pin 31 with a link 32. Such link attaches by its other end to the rod extension 33 of a shuttle-valve, and receiving this shuttle-valve is a valve chest 34. The shuttle-valve's spool element 35 is formed with two axially spaced lands, as 36 and 37, and there is provided a center-bore 38 running from the spool's forward end to a cross-bore 39 placed to the rear of the rear land 36. In the side wall of the valve chest are front and rear ports 40 and 41 and a center port 42 therebetween, and in the forward end wall is a drain opening 43, the said chest presenting end cavities allowing the spool to travel forwardly beyond the front port 40 and rearwardly beyond the rear port 41. Considered in point of center-to-center spacing, the separation as between the end ports 40 and 41 corresponds with the spacing of the two lands 36 and 37 but such lands are narrower than the ports and hence a flow of fluid is permitted when the spool occupies its neutral or centered position. The dimensions and placement of the floating lever, the shuttle-valve, and the valve chest are such that, upon a positioning of the spool in

neutral position, the pin 31 coincides with the axis of the rudder post 6.

Making connection with the forward wall port 48 are a pair of fluid-flow pipes 44 and 45 connecting, in the one instance, with the rear end of the lower starboard cylinder 13 and, in the other instance, with the forward end of the lower port cylinder 9. Return connections 46 and 47 extend between the other ends of these cylinders and the rear wall port 41. From the drain opening of the valve chest, a pipe 48 carries to an overhead relay tank 50 vented as at 51, and from this tank an overflow pipe 52 leads to a base reservoir 53. Drawing oil through a pipe 54 from this reservoir is a constant-pressure pump 55, and provided as a continuous source of power to drive this pump is an electric motor 56 (see Fig. 1). The pump feeds back through a pipe 57 to the center port 42 of the valve chest, and introduced in this pipe is a check valve 58 opening with the pressure of the pump. Between the pipe 57 and the pipe 48 are by-pass connections fitted one with a pressure-relief valve 59 and the other with a check valve 60, the check-valve closing by the pressure obtaining within the pipe 57.

Now in respect of the other cylinders 11 and 15, there are provided pipes from opposite ends of each which make connection with the two sides of a hand pump 61, and arranged and adapted to activate this hand pump through intermeshing gears 62-63 is the vessel's steering wheel 64, the desired placement of the hand pump being one in which the same is housed in the base part of the wheel stand, and in which this base serves as a reservoir for the oil being pumped by the hand pump. The hand pump is of the reversing type, and which is to say that the two sides exchange induction and eduction significance by the impartation of opposite directions of rotation to the steering wheel. Pipes leading from these two sides of the pump 61 are designated 65 and 66.

Before proceeding to describe the piping between the hand pump and the top cylinders 11 and 15, it is here stated—and which would follow a wheel mounting in which clockwise direction dictates a right rudder and, conversely, counterclockwise direction a left rudder—that clockwise directional movement of the steering wheel acts upon the hand pump such that the side connecting with the pipe 65 becomes the eduction side and the side connecting with the pipe 66 the induction side. From this pipe 65 connection is made by a pipe 67 with two branch pipes 68 and 69, and one of these branch pipes leads to the forward end of the top port cylinder 11 while the other branch pipe connects with the rear end of the top starboard cylinder 15. From the pipe 66 connection is had through a pipe 70 with two branch pipes 71 and 72, and these two branches connect with the other ends of the top cylinders, namely the pipe 71 with the rear end of the port cylinder 11 and the pipe 72 with the forward end of the starboard cylinder 15. For connecting the pump with the reservoir a nipple 73 threads into a wall opening of the latter and supplies oil to a valve body 74 having therein a double-acting check valve 75, the valve body providing separate connections one to the pipe 65 and the other to the pipe 66 with the action of the check valve being such as to automatically isolate the eduction side of the pump from the reservoir while bringing the induction side into communication therewith.

Applied to the wheel stand is the usual rudder-

angle indicator 76 suitably interconnected with the rudder post.

Assuming that the motor 16 is operating, and hence driving the pump 55 in the latter's normal continuous rotation, there then obtains a constant flow of oil from the reservoir 53 through pipe 57 and port 42 into the chest 34 and which, with the spool 35 occupying a neutral position, flows over the perimeter of the lands 36 and 37 to the two end cavities of the chest and therefrom through the pipe 48 and the relay tank 50 back to the reservoir 53. Block 25 being stationary by reason of the helmsman holding the wheel in its amidships position, any drift of the rudder with responsive slight movement of the yoke moves the floating lever's fulcrum 28 and the lever then acts about pin 24 as an axis to move the valve spool to a position which throttles the valve's oil flow, creating a pressure sufficient to hold the rudder. If the pressure builds up too high the plungers 8 and 12 will be brought into play to move the rudder ahead, and such rudder movement will move the floating lever to open the valve more. If the pressure is too low the rudder will drift back and will close the valve to increase the pressure. Thus, the floating lever connection serves to set the valve spool to a position that will throttle the pump flow to a pressure equal to that developed by rudder torque.

Assume now that the helmsman turns the steering wheel to effectuate a right rudder condition, the eduction fluid flowing through pipe 69 to the rear end of the cylinder 15 forces the pilot piston 14 forwardly and causes pin 24, which moves in unison therewith, to pivot the floating lever about pin 28 as an axis. The spool 35, responding, is made to shift rearwardly to bring the pump line 57 into communication with the rear port 41 while isolating the pump from the front port 40. The pumped oil thus feeds to the front end of the port power cylinder 9 and to the rear end of the starboard power cylinder 13 to accomplish "right rudder." Rudder movement reverses the movement of the shuttle valve to stop pump flow. If the hand pump is turned rapidly, the slide block is brought up hard against the yoke and hand energy given to the steering wheel augments the pump 55 to aid in driving the rudder. If the hand pump is made to turn slowly, the rudder will then close the shuttle valve as fast as the hand pump opens the valve, the swinging speed of the rudder consequently being in correspondence with the speed of the helm. The rudder, it will thus be seen, follows the position of the helm within the limits of the lost motion provided between block 25 and yoke arm 29, and I have engineered the system such that this lost motion is equivalent to one degree of rudder on each side of neutral, transmitting to the spool 35 a movement of 0.42" each side of neutral to assure sufficient travel for a positive valve opening, this said engineered travel of 0.42" being the maximum travel of the spool under any condition, each way considered, due to the fact that the pin 31, in the normal positioning of the floating lever, coincides with the axis of the rudder stock. The power pump which I employ is a Vickers vane type V-104 rated for continuous operation at 1000 p. s. i., and tests conducted show a minimum throttle pressure of approximately 20 p. s. i. with the negative lap on the lands of the spool of $\frac{1}{16}$ ". Inasmuch as rudder movement depends on the valve movement to obtain the throttling action which will build up sufficient pressure to hold the rudder, and $\frac{1}{16}$ " of valve

movement develops maximum throttling pressure, the rudder balances at a position within plus/minus $\frac{1}{4}$ of a degree of rudder to the position established by the pilot piston, even at hard-over rudder.

Consider that the power pump, for one reason or another, is not running, the hand-steering operation can be traced as follows: movement of the hand pump in response to, say, a counter-clockwise turning of the steering wheel causes eduction fluid to flow from pipe 66 to pipe 70 and therefrom to the forward end of cylinder 15 and the aft end of cylinder 11. The initial response is from the plunger 14 which slides the block 25 aft and pivots lever 30 about the fulcrum 28 to move the shuttle valve forwardly, thus connecting the forward and aft ends, respectively, of the power cylinders 9 and 13 with the by-pass 39-38 and the drain opening 43, and connecting the opposite ends of these said cylinders with the center port 42. Cylinders 9 and 13 are in consequence permitted to pass oil freely from one to the other end of each by a flow from the drain opening 43 into pipe 48, from pipe 48 through check valve 69 into pipe 57, and from pipe 57 to the center port 42. As this shift of the shuttle valve takes place, the rising pressure of the hand pump acts on the plungers 10 and 14 and the latter move oppositely in concert to drive the rudder into "left rudder" position as oil escapes from the forward end of cylinder 9 and the aft end of cylinder 13 and enters the opposite ends of these, the power, cylinders.

Now assume that the rudder lies hardover left and it is desired to return to neutral or amidships position. Under such condition the rudder will feed back. The handwheel turned for right rudder keeps moving the shuttle valve to keep oil draining between the diminishing-volume and increasing-volume ends of the power cylinders, and the right rudder travel continuously moves the shuttle valve back to neutral. If the rudder moves faster than the helm, the shuttle valve will go on past neutral to the forward limit of travel, in which position the ports 40 and 42 are brought into communication and oil within the forward end of cylinder 13 and the aft end of cylinder 9 is blocked against the check valves 58 and 60. The rudder will then stop moving until the helm again shifts the shuttle valve to the latter's aft limit of travel, whereupon said forward end of cylinder 13 and the aft end of cylinder 9 can again drain. It will in consequence be seen that any tendency of the rudder to over-run the helm causes the power cylinders to be blocked.

Similarly tracing the action of the shuttle valve for "right rudder" swing from neutral, the clockwise movement of the steering wheel forces eduction fluid through pipe 65 to pipe 67 and therefrom through branch pipes 58 and 69 to the forward end of cylinder 11 and the aft end of cylinder 15. A forward shift of block 25 takes place, and the floating lever 30 pivots about its fulcrum 28 to draw the shuttle valve aft. Port 40 now connects with drain opening 43 while port 41 is brought into communication with center port 42, and oil is allowed to pass from the aft end of cylinder 9 and the forward end of cylinder 13 to the drain opening and into pipe 48, thence past the check valve 60 into pipe 51, and from the latter back to the valve chest and into pipes 46 and 47 for movement into the forward end of cylinder 9 and aft end of cylinder 13.

A point of note in respect of hand-steering is

this; and which is to say that while there is $\frac{1}{4}$ of lost motion in the slide connection between the plunger rod 23 of the pilot piston 14 and the arm of the yoke 1, the tight connections from the other three plungers to the yoke keep the rudder from swinging freely.

It should, perhaps, be remarked that the relief valve 59 is installed solely to protect the pump and to relieve rudder shock, it being unnecessary that recourse be had to a valve of this nature as a means of constantly controlling the pressure of the pump in that the pump pressure is regulated by the shuttle valve 35.

The system, and the manner of its operation, are believed to be clear from the foregoing. Departures from the embodiment which I have elected to illustrate, departures that is in the sense of the details of construction, will more or less suggest themselves. It is accordingly my intention that all forms of construction and variations in detail coming within the scope of the hereto annexed claims are to be considered as comprehended by the invention.

What I claim is:

1. In a hydraulic steering system having a power motor and a pilot motor, each actuated by pressure fluid and each operatively interconnected with the vessel's tiller, the one directly and the other through a lost-motion connection; a continuously driven unidirectional-flow main pump; a reversible-flow manually operable transmitter pump; fluid-flow connections one from one side of the transmitter pump to one end of the pilot motor and the other from the other side of the transmitter pump to the other end of the pilot motor; a control valve providing a valve spool and a four-way valve body for the spool; fluid-flow pipes connecting two of the four ports of the four-way valve body with opposite ends of the power motor; fluid-flow pipes connecting the remaining two ports of the valve body one with the induction side and the other with the eduction side of the main pump, the arrangement as between the valve spool and said ports being such that pressure fluid is given free passage between eduction and induction sides of the main pump upon a neutral positioning of the spool and serves to connect said eduction side with one end and the induction side with the other end of the power motor, selectively, by movements of the spool in opposite directions from neutral; a mechanical connection from the pilot fluid-motor to the valve spool acting by operation of the former taking up the lost motion in said motor's connection with the tiller to move the spool from neutral, thus to activate the power motor and drive the tiller, and by a responsive overtake by the tiller of said lost-motion travel of the pilot motor to move the spool back to neutral, said tiller being comprised of a yoke with both the power motor and the pilot motor each having their connection with one end of said yoke, and means to augment said described motors comprising a second motor made responsive to the pressure of the main pump and a second motor made responsive to the pressure of the transmitter pump, the two motors last named being each direct-connected to the other end of the yoke.
2. In a hydraulic steering system having a power motor and a pilot motor, each pressure-fluid actuated and comprised of a double-acting piston and a closed cylinder therefor and each operatively interconnected with the vessel's tiller, the one directly and the other through a lost-

motion connection; a continuously driven main pump; a reversible-flow manually operable transmitter pump; fluid-flow connection from one side of the transmitter pump to one end of the pilot motor's cylinder and from the other side of the transmitter pump to the other end of said cylinder; a shuttle-type control valve providing a valve spool and a four-way valve body for the spool; fluid-flow pipes connecting two of the four ports of the four-way valve body one to one end and the other to the other end of the power motor's cylinder; fluid-flow pipes connecting the remaining two ports of the valve body one with the induction side and the other with the eduction side of the main pump, the arrangement as between the valve spool and said ports being such that pressure fluid is given free passage between eduction and induction sides of the main pump upon a neutral positioning of the spool and serves to connect said eduction side with one end and the induction side with the other end of the power motor's cylinder, selectively, by movements of the spool in opposite directions from neutral; a mechanical connection from the pilot motor to the valve spool functional by such activation of the former as takes up the lost motion in said motor's connection with the tiller to move the spool from neutral, thus to activate the power motor and drive the tiller, and by a responsive overtake by the tiller of said lost-motion travel of the pilot motor to move the spool back to neutral.

3. In a hydraulic steering system having a power motor and a pilot motor, each pressure-fluid actuated and each operatively interconnected with the vessel's tiller, the one directly and the other through a lost-motion connection; a continuously driven main pump; a reversible-flow manually operable transmitter pump; fluid-flow connections from respective sides of the transmitter pump to the pilot motor acting by flow of pressure fluid through one to activate the pilot motor for operation in one direction and by flow of pressure fluid through the other to activate the pilot motor for operation in the other direction; a shuttle-type control valve providing a valve spool and a four-way valve body for the spool; fluid-flow pipes connecting two of the four ports of the four-way valve body with the power motor, the delivery of pressure fluid through one of said pipes activating the power motor for operation in one direction and the delivery of pressure fluid through the other of said pipes activating the power motor for operation in the other direction; fluid-flow pipes connecting the remaining two ports of the valve body one with the induction side and the other with the eduction side of the main pump, the arrangement as between the valve spool and said ports being such that pressure fluid is given free passage between eduction and induction sides of the main pump upon a neutral positioning of the spool and serves to connect said eduction side with one and the induction side with the other of said two pipes which connect with the power motor, selectively, by movements of

the spool in opposite directions from neutral; a fluid-flow pipe connecting eduction and induction sides of the main pump and fitted with a check valve closing with the pressure of the pump; and a mechanical connection from the pilot motor to the valve spool functional by such activation of the former as takes up the lost motion in said motor's connection with the tiller to move the spool from neutral, thus to activate the power motor and drive the tiller, and by a responsive overtake by the tiller of said lost-motion travel of the pilot motor to move the spool back to neutral.

4. In a hydraulic steering system having a power motor and a pilot motor, each pressure-fluid actuated and comprised of a double-acting piston and a cylinder therefor and each operatively interconnected with the vessel's tiller arm, the one by a positive connection and the other by a lost-motion connection, said positive connection comprising a piston rod and a wrist pin therefor which is held stationary with respect to the tiller arm, and said lost-motion connection comprising a piston rod and a wrist pin therefor which is given limited slide movement in respect of the tiller arm; a continuously driven main pump; a reversible-flow manually operable transmitter pump; fluid-flow connection from one side of the transmitter pump to one end of the pilot motor's cylinder and from the other side of the transmitter pump to the other end of the pilot motor's cylinder; a shuttle-type control valve providing a valve spool and a four-way valve body for the spool; fluid-flow pipes connecting two of the four ports of the four-way valve body one to one end and the other to the other end of the power motor's cylinder; fluid-flow pipes connecting the remaining two ports of the valve body one with the induction side and the other with the eduction side of the main pump, the construction of said valve spool and its relation to said ports being such that pressure fluid is given free passage between eduction and induction sides of the main pump upon a neutral positioning of the spool and, by movements of the spool in opposite directions from neutral, serves to connect said eduction side with one end and the induction side with the other end of the power motor's cylinder, selectively; a fluid-flow pipe connecting eduction and induction sides of the main pump and fitted with a check valve closing with the pressure of the pump; and a connection from the said slidably mounted wrist pin to the valve spool functional by such activation of the pilot motor as takes up the lost motion between wrist pin and tiller arm to move the spool from neutral, thus to activate the power motor and drive the tiller, and by a responsive overtake by the tiller of said lost-motion travel of the slidably mounted wrist pin to move the spool back to neutral.

5. Structure according to claim 4 wherein said spool-moving connection comprises a floating lever fulcrumed intermediate its length to the tiller arm and connected by its outer end to the slidably-mounted wrist pin and by its inner end to a link which is in turn connected to the spool, the connection from the inner end to the link comprising a pivot pin disposed to have its axis coincide with the axis of the vessel's rudder post upon a positioning of the sliding wrist pin at the mid-point of its sliding movement.

6. In a hydraulic steering system having a power motor and a pilot motor, each pressure-

fluid actuated and comprised of a double-acting piston and a cylinder therefor and each operatively interconnected with the vessel's tiller, the one by a positive connection and the other by a lost-motion connection; a continuously driven main pump; an oil reservoir supplying fluid to the induction side of said pump; a reversible-flow manually operable transmitter pump; fluid-flow connections one from one side of the transmitter pump to one end of the pilot motor's cylinder and the other from the other side of the transmitter pump to the other end of said cylinder; a control valve providing a valve spool and a four-way valve body for the spool; fluid-flow pipes connecting two of the four ports of the four-way valve body with opposite ends of the power motor's cylinder; fluid-flow pipes connecting the remaining two ports of the valve body one with the oil reservoir and the other with the eduction side of the main pump, the arrangement as between the valve spool and ports being such that pressure fluid is given free passage between the eduction side of the main pump and the reservoir upon a neutral positioning of the spool and, by movements of the spool in opposite directions from neutral, serves to connect said eduction side with one end of the power motor's cylinder and to connect said reservoir with the other end of the power motor's cylinder, selectively; a fluid-flow by-pass pipe connecting said pipe which leads from the eduction side of the main pump with said pipe which leads to the reservoir and fitted with a check valve closing with the pressure of the pump; and a connection from the pilot motor to the valve spool functional by such activation of the pilot motor as takes up the lost motion between pilot motor and tiller to move the spool from neutral, thus to activate the power motor and drive the tiller, and by a responsive overtake by the tiller of said lost-motion travel of the pilot motor to move the spool back to neutral.

7. The hydraulic steering system of claim 6 having a check valve arranged to open with the pressure of the main pump and fitted in the pipe which leads from the eduction side of the latter to occupy a position between said pump and the point of connection with said by-pass pipe.

8. The hydraulic steering system of claim 6 having a separate oil reservoir for the fluid-flow system which includes the transmitter pump, the cylinder of the pilot motor, and the pipes therebetween, and wherein means are provided between said transmitter pump and its said reservoir and operating automatically by manual activation of the transmitter pump in either of its converse directions of flow for connecting the reservoir with the induction side of the pump while isolating the reservoir from the eduction side of the pump.

9. The hydraulic steering system of claim 6 having a relay tank disposed to occupy a position above the upper limit of the power motor and the control valve, and wherein said pipe connection from the four-way valve body to the reservoir leads to the overhead relay tank and therefrom, by an overflow connection, to the reservoir.

10. In a hydraulic steering system, in combination with the rudder stock of a vessel, and a yoke attached thereto: a pair of power motors of a fluid-actuated nature direct-connected one with one and the other with the other arm of the yoke and disposed to occupy positions one at one side and the other at the other side of a longitudinal median traversing said rudder stock, said motors

being comprised in each instance of a double-acting piston and a cylinder for the piston; a second pair of fluid-actuated motors each similarly comprised of a double-acting piston and a cylinder therefor and likewise placed at opposite sides of said longitudinal median and connected to related arms of the yoke, one of said connections being direct and the other lost-motion; a continuously driven main pump; an oil reservoir connecting with the induction side of said pump; a reversible-flow manually operable transmitter pump; fluid-flow pipes connecting one side of the transmitter pump to the aft end of one and the forward end of the other of the two cylinders last mentioned, and connecting the other side of the transmitter pump to the opposite ends of said cylinders; a four-way valve body, and a control valve housed in said body; fluid-flow pipes connecting one of the four ports of the four-way valve body with the eduction side of the main pump, connecting a second of the four ports with the oil reservoir, connecting a third of the four ports with the aft end of one and the forward end of the other of the two cylinders first mentioned, and connecting the remaining port with the opposite ends of said power cylinders, the construction of said control valve and its relation to the four ports being such that pressure fluid is given free passage from the main pump back to the reservoir upon a neutral positioning of the valve and, by movements of the valve in opposite directions from neutral, serves to connect the eduction side of the pump with a selected one of the two cylinder-connecting ports while bringing the other said cylinder-connecting port into communication with the port which feeds back to the reservoir; a fluid-flow by-pass pipe connecting the pipe which feeds back to the reservoir with the pressure pipe from the eduction side of the main pump, and fitted with a check valve closing with the pressure of the main pump; and an operating connection, to the control valve, from the motor which has lost-motion connection with the yoke, said operating connection being arranged and adapted, by such an activation of the motor as takes up the lost motion, to move the control valve from neutral, thus to activate the power motors and drive the yoke, and by a responsive overtake from the yoke of said lost-motion travel to move the control valve back to neutral.

11. A hydraulic steering system comprising a power motor and a pilot motor each pressure-fluid actuated and each connected with the vessel's tiller arm the former said motor by a positive connection and the latter said motor by a lost-motion connection; a system for continuously circulating a pressure fluid and including a continuously driven uni-directional main pump, said system being functionally associated with but normally inactive to the power motor; a transmitter pump functionally associated with and made active at will to the pilot motor; and a control valve for said pressure-fluid system hooked to the pilot motor for direct response to the operations of the latter and characterized in that the same is made instantly effective to bring the main pump into operating couple with the power motor by such an activation of the pilot motor as takes up said lost motion and to operatively uncouple the main pump from the power motor as the activated tiller arm responsive overtake said lost-motion travel, said hook-up as between the control valve and the pilot motor comprising control rods connected

one with the pilot motor and the other with the control valve and each placed to occupy a position angular to the tiller arm, a floating lever fulcrumed to the tiller arm for rocker movement about an axis offset from but parallel to the turning axis of the tiller arm and pivotally connected to said control rods at separated points offset from the fulcrum of the lever, one of said pivotal connections being permitted a limited slide movement in relation to the tiller arm and the other said pivotal connection being so placed that its axis coincides with the turning axis of the tiller arm upon a positioning of the sliding pivot at the approximate mid-point of its sliding movement.

12. A hydraulic steering system comprising a power motor and a pilot motor each pressure-fluid actuated and each connected with the vessel's tiller arm the former said motor by a positive connection and the latter said motor by a lost-motion connection, said positive connection comprising a piston rod and a wrist pin therefor which is held stationary with respect to the tiller arm and said lost-motion connection comprising a piston rod and a wrist pin therefor which is given a limited slide movement in respect of the tiller arm; a continuously driven main pump functionally associated with and made active at will to the pilot motor; and a control valve for the main pump hooked to the pilot motor for direct response to the operations of the latter and characterized in that the same is made instantly effective to bring the main pump into operating couple with the power motor by such an activation of the pilot motor as takes up said lost motion and to operatively uncouple the main pump from the power motor as the activated tiller arm responsively overtakes said lost motion travel, said hook-up as between the control valve and the pilot motor comprising control rods connected one with the pilot motor and the other with the control valve and each placed to occupy a position angular to the tiller arm, a floating lever fulcrumed to the tiller arm for rocker movement about an axis offset from but parallel to the turning axis of the tiller arm and pivotally connected to said control rods at separated points offset from the fulcrum of the lever, one of said pivotal connections being permitted a limited slide movement in relation to the tiller arm and the other said pivotal connection being so placed that its axis coincides with the turning axis of the tiller arm upon a positioning of the sliding pivot at the approximate mid-point of its sliding movement.

13. A steering system comprising a power motor pressure-fluid actuated and direct-connected to the vessel's tiller arm for unitary movement with the latter; a manually governed pilot motor having lost-motion connection with the tiller arm; a continuously driven pump functionally associated with but normally inactive to the power motor; and a control valve for the pump positively hooked to the pilot motor for direct response to the operations of the latter and characterized in that the same is made effective to bring the pump into operating couple with the power motor by such an activation of the pilot

motor as takes up said lost-motion and to operatively uncouple the pump from the power motor by a responsive overtake from the activated tiller arm of said lost-motion travel, said hook-up as between the control valve and the pilot motor comprising control rods connected one with the pilot motor and the other with the control valve and each placed to occupy a position angular to the tiller arm, a floating lever fulcrumed to the tiller arm for rocker movement about an axis offset from but parallel to the turning axis of the tiller arm and pivotally connected to said control rods at separated points offset from the fulcrum of the lever, one of said pivotal connections being permitted a limited slide movement in relation to the tiller arm and the other said pivotal connection being so placed that its axis coincides with the turning axis of the tiller arm upon a positioning of the sliding pivot at the approximate mid-point of its sliding movement.

14. A hydraulic steering system comprising a power motor of a double-acting nature operated by pressure fluid and direct-connected to the vessel's tiller arm for unitary movement with the latter; a manually governed pilot motor having lost-motion connection with the tiller arm; a continuously driven and uni-directional main pump; fluid-flow connections normally isolated from the pump and connecting one with one end and the other with the other end of the power motor; a control valve arranged to selectively bring said fluid-flow connections one into communication with the high-pressure side and the other into communication with the low-pressure side of the pump; and a system of rigid links hooking the valve to the pilot motor for direct response to the operations of the latter and also having operative interconnection with the tiller arm such that turning movements of the tiller arm modify the action of the linkage and transmit movement to the control valve, said hook-up as between the control valve and the pilot motor comprising control rods connected one with the pilot motor and the other with the control valve and each placed to occupy a position angular to the tiller arm, a floating lever fulcrumed to the tiller arm for rocker movement about an axis offset from but parallel to the turning axis of the tiller arm and pivotally connected to said control rods at separated points offset from the fulcrum of the lever, one of said pivotal connections being permitted a limited slide movement in relation to the tiller arm and the other said pivotal connection being so placed that its axis coincides with the turning axis of the tiller arm upon a positioning of the sliding pivot at the approximate mid-point of its sliding movement.

PAUL E. FORSYTHE.
